UNITED STATES PATENT OFFICE

2,510,633

ROTOR CONSTRUCTION FOR ENSILAGE CUTTERS

George B. Hill, Ottumwa, Iowa, assignor to Deere Manufacturing Co., Dubuque, Iowa, a corporation of Iowa

Application March 1, 1948, Serial No. 12,418

4 Claims. (Cl. 146—108)

1

This invention relates to an improved rotor construction for an ensilage cutter or like means. More particularly, the invention relates to improved hub structure for such rotors and to improved means for carrying the blades or knives of the cutter.

In an ensilage cutter or like means, material to be cut is fed along a defined path toward a cutting rotor which is mounted for rotation on an axis generally parallel to the path of material feeding, and a plurality of radial blades or knives on the rotor cooperate with a transverse shear bar, over which the material is fed, to reduce the material. Rotor constructions in general are of two well known types; in one type the rotor comprises a disk of relatively large diameter and to one face of which is attached a plurality of radial knives or blades; in another type of rotor, the basic components thereof include a central hub structure from which a plurality of arms extend radially to carry the cutting knives. In a rotor of the first type, the circular disk places a definite limitation upon the lengths into which the material can be cut, since the circular disk forms a stop past which the material cannot move as it is fed to the rotor or cutter housing. In the second type of rotor, the knife-carrying arms provide spokes and do not establish stops limiting the inward feeding of the material. In either case, however, the manner in which the knife is carried on the rotor may seriously affect the feeding and cutting of material, inasmuch as the knife must be carried at that face of the rotor toward which the material is fed; and, as a practical matter, the supporting structure for such knife is necessarily carried at the same face. It is desirable, therefore, that such supporting structure be of such nature that it can be arranged as remotely as possible from the general plane of cutting, which plane is normal to the rotating axis of the rotor and includes the cutting edges of the knives and the transverse edge of the shear bar.

The principal object of the present invention is to provide an improved knife-carrying structure which meets the foregoing requirements and enables the rotor to be constructed in such manner as to accommodate adjustment in the feeding mechanism to cut the material into desired lengths, and particularly into longer lengths than have been heretofore obtainable. Another object of the invention relates to improved means for adjusting the cutting knives, such means being disposed relatively remote with respect to the general cutting plane.

Rotors of the general type referred to operate

2

at relatively high speeds and therefore must have the capacity to withstand the tendency to disintegrate during operation. This desired result can, of course, be obtained by heavier types of constructions, but it is found that meeting the requirement in this manner increases the size and cost of the rotor. Accordingly, it is another object of the invention to provide an improved rotor construction preferably comprising a fabricated structure in which the components are rigidly secured together, as by welding, and to utilize in this structure specially selected material sections determined to give the greatest strength at the lowest cost consistent with requirements set up by manufacturing and operating conditions. In this respect, it is another object of the invention to provide a construction that is light in weight but which does not sacrifice the necessary inertia characteristics that must be retained to provide for the most efficient operation of the rotor.

The foregoing and other desirable and important objects and features encompassed by and inherent in the invention will become apparent to those skilled in the art as a disclosure is more fully made of a preferred form of the invention in the following detailed description and the accompanying sheets of drawings, in which

Figure 1 is a general front elevational view, with portions broken away to conserve space in the drawing, of that side of the improved rotor toward which the material is fed;

Figure 2 is an elevational view, partly in section, as viewed along the line 2—2 of Figure 1;

Figure 3 is a transverse sectional view, on an enlarged scale, taken substantially along the line 3—3 of Figure 2 and showing the back side of the rotor hub structure;

Figure 4 is a schematic view showing an enlarged detail of the knife and knife-supporting structure, together with illustrations of portions of the feeding mechanism and the shear bar with which the knife cooperates;

Figure 5 is a fragmentary perspective view taken from that side of the rotor toward which the material is fed and showing the details of a knife and knife-supporting member; and

Figure 6 is a similar perspective view showing the knife-supporting member per se.

The ensilage cutter or other machine in which the improved rotor construction may be used may be of any well known construction and unessential details thereof have been omitted from the present illustration. In Figure 4 there are shown certain of the basic parts common to such machine. The numerals 10 and 11 indicate, respectively, upper and lower feed rolls which

comprise part of feeding mechanism for feeding material along a generally defined path AB toward a rotor or cutter, designated generally by the numeral 12, carried in a suitable housing (not shown). The direction of material feeding is indicated by the arrow, as are the directions of rotation of the feed rolls 10 and 11. The material fed along the path AB passes over a transverse shear bar 13 having a transverse front edge which lies in a plane generally normal to the path AB and designated in Figure 4 by the line CD. The construction described thus far may be very similar to that shown in U. S. Patent 2,313,872.

The improved rotor construction comprises a central structure or hub including a rotor shaft 14 and first and second plates 15 and 16. Each of the plates is in the form of a perfect square and each is centrally apertured to receive the rotor shaft 14. The plate 15 is rigidly secured to the shaft 14 for rotation therewith, the securing means preferably including welding, as at 17 (Figure 2). The plate 16 is likewise secured, as by welding at 18, to the shaft 14, the two plates being disposed on the shaft in an axially spaced relation to provide a pair of radial portions extending from the shaft. The plates are mounted on the shaft 14 in such manner that the diagonal of the plate 15 is angularly related to the diagonal of the plate 16, the purpose of which will appear below. The plate 16 is also considerably larger than the plate 15.

The plates 15 and 16 provide the basic hub structure of the rotor and further provide means for carrying four generally radially extending knife-supporting structures or arms, each indicated generally by the numeral 19. Since each knife-supporting structure or arm 19 is similar in construction, only one will be described and it will be understood that the details thereof are repeated in the other structures. Each arm 19 is in the form of an angle iron having first and second angularly related flanges 20 and 21 (Figure 6). The angle iron is mounted on the hub structure between the plates 15 and 16 in such manner as to extend generally radially therefrom, with the principal axis of the arm forming, in effect, an extension or continuation of the edge of the small plate 15, it being understood that the four sides of the square plate serve in this manner to locate and mount the four arms 19. The outer surface of the flange 21 is rigidly secured to the proximate portion of the inner face of the square plate 15, preferably by welding along a line indicated generally by the numeral 22 in Figure 5. The flange 21 is preferably divided into a first portion 23 at the inner end of the arm 19 and a comparatively longer portion 24 (Figure 6) at the outer portion of the arm 19. The relationship between the first flange 20 and the first portion 23 of the second flange 21 is such that the flange portion 23 is at a right angle to the flange 20, the former extending integrally into the latter through an intermediate portion 25 which is inclined to both the flange 20 and the first flange portion 23. The outer flange portion 24 is separated from the flange portions 23-25 by a slot 26 and the general inclination thereof is such as to place this flange portion at an obtuse angle to the uninterrupted flange 20. An examination of Figures 3, 4, 5 and 6 will show the relationship between the portions referred to and will further indicate that the slot 26 is, when the arm 19 is assembled on the plate 15, substantially at the edge of the square plate 15 which

is at right angles to the edge along which the arm 19 has its principal axis. The three edges bounding the inner flange portion 23 are rigidly secured to the inner face of the plate 15, preferably by welding, as indicated at 27 in Figures 3 and 5.

Since the arms 19 are located on or with respect to the small plate 15 in such manner as to extend respectively from the four edges or sides of the square defining the plate 15, the inner portions of the arms meet and are related, as in Figure 3, to define a square around the intermediate portion of the shaft 14. The inner end portions of the arms 19 abut and are secured together, as by welding along the lines indicated at 28. The welding of the inner ends of the arms at 28 to each other will coincide somewhat with the welding of the portions 23 along the lines 27 as referred to above. In addition, the inner end portions of the arms are welded to the shaft 14 at the location designated by the numeral 29.

The arrangement with respect to the inner portion of the arms 19 and the plates 15 and 16 is such that the flange portion 23 is secured to the inner face of the plate 15 as aforesaid. The proximate portion of the flange 20 extends axially away from the plate 15 and toward the plate 16, thus providing an axial projection which presents a free edge lying along the inner face of the larger plate. Inasmuch as the plate 16 is turned on the shaft with respect to the plate 15 so that the diagonals of the two squares are angularly related, the four corners of the larger square lie on the projected edges of the flanges 20 just referred to, as at 30 (Figure 1). The disposition of the larger plate 16 in this manner provides the greatest radial extent of the plate with respect to the supporting of the arms 19. This edge of the flange 20 is welded to the inner face of the plate 16, as at 31 (Figure 1), and also at 32 (Figure 4).

The hub structure is thus of strong, light weight construction and does not rely upon the use of expensive and heavy castings. The manner of securing together the components comprising the arms 19 and plates 15 and 16 and shaft 14 is such that these parts tend to mutually reinforce each other.

The radially outwardly extending portion of each arm 19 that includes the angularly related flange portions 20 and 24 provides means for supporting a cutting blade or knife, indicated generally by the numeral 33. As best seen in Figure 4, the inclination of the flange portion 24 is such as to present at the outer face of the flange a surface 34 that is inclined in a leading direction and toward the general cutting plane CD. The knife 33 is a plate-like element which has inner and outer surfaces, the inner surface being mounted on the outer surface 34 of the flange 24 and the outer surface being presented to the incoming material fed by the feed rolls 10 and 11 over the shear bar 13. The knife 33 is provided with a leading angularly related portion 35 which is ground on the inside, at 36, to provide a sharpened leading or cutting edge. The trailing portion of the knife 33, or that portion thereof that extends axially inwardly away from the cutting plane CD, lies closely parallel or along the juncture between the flange portions 20 and 24, as indicated in Figure 4 at 37.

Each knife-supporting arm 19 is provided with means for carrying the knife for adjustment. This means is best shown in Figure 5 as including a pair of angled members 38, each having

a first leg portion 39 and a second leg portion 40. The leg portion 39 lies on top of the flange 20 and is apertured and recessed to receive a pair of cap screws 41 which are threaded into appropriately tapped bores 42 in the flange 20. The juncture of the legs 39 and 40 provides a slightly offset portion 43, the interior of which is spaced in a trailing direction with respect to the trailing edge 37 of the knife 33. This portion 43 is drilled and tapped at 44 to receive an adjusting screw 45 forming part of an adjusting device for adjusting the knife 33. The adjusting screw 45 further includes a lock nut 46 threaded thereon.

As best shown in Figure 4, the leg 40 is so related to the flange portion 24 that the two portions form generally a bifurcated structure defining a slot within which the knife 33 is carried, the closed end of the slot being defined by the portion 43 of the angled member 38 and the open end of the slot being disposed in a leading direction so that the knife 33 may project therefrom. Each leg portion 40 of the angled member 38 is provided with a tapped bore 47 which is aligned with an aperture 48 in the flange portion 24. A cap screw 49 passes through the aperture 48, through a slot 50 in the knife 33 and is threaded into the tapped bore 47 in the angled member 38.

The leading edge of the leg 40 on each angled member 38 is ground off, as at 51, to remove it as far as possible from the cutting plane CD. Likewise, the inner leading edge of the flange portion 24 is ground off at 52 to give the greatest possible effect to the leading or cutting edge of the knife 33. The inclination of the outer surface of the angled member 38 is the same as that of the knife 33 and the outer or mounting surface 34 of the flange 24, as is the axis of the adjusting screw 45. The arrangement is such that the mounting and adjusting components are relatively remote from the cutting plane CD and are substantially ineffective as positive stops for incoming material fed by the feed rolls 10 and 11; that is to say, if it is desired to cut the material in relatively long lengths, the supporting and adjusting components for the knife 33 are so remotely positioned axially inwardly of the cutting plane CD as to form practically no obstacle to the inward movement of material along the path AB, it being borne in mind that the rotor is of the spoked type (including arms 19). Material cut by the knives is propelled through the usual discharge duct (not shown) by means of paddles 53, one welded to the outer end of each arm 19.

The foregoing description is, of course, based upon only a preferred embodiment of the invention and the description of the structural aspects thereof and the objects achieved thereby is not intended to exclude variations but rather to explain the basic principles of the invention in a manner that will enable the invention to be intelligently practiced. The present disclosure should therefore be taken as illustrative and not restrictive.

What is claimed is:

1. In a machine of the class described including a rotor and means for feeding material axially inwardly thereto, the improvement comprising: a knife support on the rotor including a first surface extending radially outwardly from the axis of the rotor and inclined to the general plane of rotation thereof in a leading direction and axially outwardly thereof, and further having a second angularly related and trailing surface extending axially inwardly from the first sur-

face; a plate-like knife extending radially along the knife support and having inner and outer surfaces, the former of which lies on the first surface of the knife support so that the knife has substantially the same inclination as said surface and extends therefrom in a leading direction to provide a leading sharpened edge and further having a trailing edge generally at the juncture of said first and second surfaces; an angled member having one leg engaging the outer surface of the knife and terminating short of the leading edge thereof, and a second leg extending axially inwardly over the trailing edge of the knife and overlying the aforesaid second surface of the knife support; means securing said second leg to the knife support at said second surface; means, including a fastening element and slot, adjustably securing the knife to the first surface of the knife support and also to the first leg of the angled member; and an adjusting member movably carried by the second leg and engaging the trailing edge of the knife for shifting the knife in a leading direction.

2. The invention defined in claim 1, further characterized in that: the knife support comprises an angle iron having angularly related flanges providing the aforesaid first and second surfaces.

3. In a machine of the class described, a rotor construction comprising: a shaft; first and second generally parallel plates axially spaced apart and rigidly secured to the shaft; a plurality of arms extending generally radially outwardly from the shaft axis, each arm comprising an angle iron having first and second right-angled flanges at its radially innermost end fitting between the plates, the first of said flanges extending axially across between the plates and having a free edge lying along the first plate and an opposite edge that joins the second flange lying along the second plate, and the second flange lying flat against said second plate; means securing the free and opposite edges of the first flange respectively to said plates; means securing the second flange to said second plate; said first flange extending radially from the plates and lying in the same plane generally throughout its length, and the second flange also extending radially from the plates but bent just outwardly of the plates along its juncture with the first flange to form an obtuse angle with said first flange.

4. In a machine of the class described, a rotor construction comprising: a shaft; a rotor hub including first and second generally parallel radial portions axially spaced apart and rigidly secured to the shaft; a plurality of arms extending generally radially outwardly from the shaft axis, each arm comprising an angle iron having first and second right-angled flanges at its radially innermost end fitting between the radial portions, the first of said flanges extending axially across between the radial portions and having a free edge lying along the first radial portion and an opposite edge that joins the second flange lying along the second radial portion, and the second flange lying flat against the second radial portion; means securing the free and opposite edges of the first flange respectively to the first and second radial portions; means securing the second flange to said second radial portion; said first flange extending radially from the radial portions and lying in the same plane generally throughout its length, and the second flange also extending radially from the plates but bent just

outwardly of the hub along its juncture with the first flange to form an obtuse angle with said first flange.
